United States Patent Office.

E. F. MALLORY, OF WEST SPRINGFIELD, PENNSYLVANIA.

Letters Patent No. 68,520, dated September 3, 1867.

IMPROVED BURGLAR-ALARM.

The Schedule referred to in these Letters Patent and making part of the same.

TO ALL WHOM IT MAY CONCERN:

Be it known that I, E. F. MALLORY, of West Springfield, in the county of Erie, and State of Pennsylvania, have invented a new and useful Improvement in Burglar-Alarm; and I do hereby declare that the following is a full, clear, and exact description thereof, which will enable those skilled in the art to make and use the same, reference being had to the accompanying drawings, forming part of this specification.

The present invention relates to a burglar-alarm that is so constructed and arranged in its several parts that as the door or window is opened to which it is applied an alarm will be sounded, as will be now described, reference being had to the accompanying plate of drawings, in which—

Figure 1 is a side view of the device, and

Figure 2 a plan or top view.

A, in the drawings, represents a spring having two arms, B and B², loose at one end, but at the other formed into one and the same coil C, for imparting a spring to the arm B². To the loose end of arm B a screw, D, is fixed by means of which the spring is fastened in place about a door or window; the head E to this screw forming an anvil, as it were, for the end of the right-angular bent portion F to the other arm B² to strike upon. This end to bent portion F is for carrying a percussion-cap or other explosive medium. G, a loop arranged to slide upon and over arm B² to spring A, around the sides of which it extends, and along its length, toward the anvil-head of screw, where, being joined together, it passes over the surface of anvil-block E between it and the nipple-head F, with such nipple-head resting upon its inclined surface H, and terminates in a hook, I, at its extreme outer end.

In the attachment of the burglar-alarm above described to a door, first insert the screw in the door-casing up to its shoulder J, or thereabouts, and at about a foot or so above the knob or latch, leaving it straight or across the casing, when, draw the hook-loop forward until its shoulder K abuts against the head to the said screw, and then secure it by its hook I into the door a short distance from its edge. Now, if the door is opened, the end of the spring which rests upon the said screw-head will be raised, when the part attached to the door, becoming detached from the part on the door-casing, the arm B² is left free to fall upon the screw-head, whereby the cap on the nipple-end thereto will be snipped or exploded, producing an alarm.

I claim as new, and desire to secure by Letters Patent—

The combination of the spring A, provided with anvil-head, in combination with hook-loop, when both are constructed and arranged together for operation, substantially as and for the purpose described.

E. F. MALLORY.
